PROCESS OF PURIFYING HYDROCARBONS

Application filed June 7, 1927. Serial No. 197,150.

This invention relates to the purification of hydrocarbons, and while not necessary thereto, it more specifically refers to the treatment of naphtha or gasoline synthetically produced by the cracking of hydrocarbon oils, such as petroleum or shale oil, or distillates derived from a relatively high sulphur bearing crude oil in which free sulphur, hydrogen sulfide, or mercaptans may be formed during 5 said distillation or cracking operation, are present in the final distillate.

One of the principal objects of this invention is to accomplish a desulphurizing and purification of gasoline stock by a sequence 15 of operations, to accomplish this purification rapidly and economically. Another object of this invention is to provide a continuous process or batch system for the extraction of free sulphur, hydrogen sulfide and mercaptans from gasoline stocks containing the same, by the employment of a metal dioxide in an alkaline aqueous suspension, commingling said alkaline aqueous suspension of metallic dioxide with the gasoline stock under 20 treatment, whereby free sulphur, hydrogen sulfide and mercaptans are oxidized with the formation of compounds having higher boiling points which may be thereafter separated by a fractional distillation process.

Another object of the invention is to produce a stable "sweet" gasoline stock by treating a "sour" gasoline with an excess of manganese dioxide-aqueous alkaline suspension to convert the sulphur compounds 25 contained in the gasoline which has the properties of producing a "sour" reaction to compounds that do not give this reaction, thus resulting in a "sweet" gasoline. Furthermore, certain sulphur compounds are converted to compounds of higher boiling point which on subsequent distillation are removed by virtue of the increase in boiling point. The type of chemical reaction in its simplest form which may take place in the above step is as follows:

With the foregoing preliminary explana-

tion, the preferred embodiment of our invention will now be more fully explained by reference to the accompanying drawing, which is a diagrammatical representation of an apparatus in which the invention is to be carried out.

In the drawing 1 indicates generally a gasoline supply tank containing the stock to be treated, which is connected by a pipe 2 near the bottom and leads to the suction side of a pump 4 controlled by a valve 3. Pump 4 discharges through the pipe 5 into the exchanger 6. A pipe 7 connects exchanger 6 with a pipe 8. The said pipe 8 is connected to heater 9. Heater 9 is connected to a steam pipe 43 which leads to a source of steam not shown. 44 is a pipe connecting to said heater 9 and leads to a source of waste steam not shown. Pipe 10 connects the heater 9 to a reaction chamber 11. The reaction chamber 11 is provided with three outlet pipes 12, 14 and 16 controlled by the three valves 13, 15 and 17, which are connected to the pipe 18. The pipe 18 is connected to the suction side of a pump 19, which discharges into a pipe 20 which is connected to branch pipes 22 and 24, controlled by the valves 21 and 23. The branch pipe 22 is connected to exchanger 6. Exchanger 6 is connected to a cooler 45 by the pipe 25. The said cooler 45 is provided with water inlet and outlet pipes 41 and 42. The pipe 26 connects the cooler 45 to separator 27. A pipe 30 connects the separator 27 at the bottom to a tank 32 controlled by valve 31. A pipe 33 connects tank 32 at the bottom, controlled by a valve 34, and leads to a recovery plant not shown. A pipe 28 connects the separator 27 at the top to treated oil tank 29. A pipe 40 is connected to the treated oil tank 29 at the bottom controlled by a valve 39 and leads to a storage not shown.

46 is mixer provided with a caustic inlet pipe 37 and an air inlet pipe 38. This mixer 46 is provided with steam coils 50 which lead to a source of steam not shown. A pipe 36, controlled by valve 35 connects a mixer 46 on the suction side of pump 47. Pump 47 discharges into the pipe 8 which is connected to the said heater 9.

The preferred process as carried out with 100

the apparatus just described, is as follows:

Gasoline or naptha stock to be treated, contained in the tank 1, is discharged by the pump 4 through a heat exchanger 6, passing through pipes 5 and 7. The untreated oil passing through the heat exchanger 6 enters into a heat exchange with the treated oil coming from the reaction chamber 11 where a temperature of approximately 100 to 150° F. is attained. From heat exchanger 6 the oil to be treated passes into a pipe 8 where it meets a stream of water solution of caustic alkali containing suspended manganese dioxide heated to a temperature of approximately 200 to 220° F., and is commingled therewith and further heated to the reaction temperature which may vary from 200 to as high as 350° F. under a pressure sufficient to prevent any substantial vaporization of the hydrocarbons or aqueous alkali solution, during the passage through the heater 9. The commingled oil and water solution of caustic soda containing the suspended manganese dioxide heated to the reaction temperature, 200 to 350° F. pass under pressure sufficient to prevent vaporization from the heater 9 into a reaction chamber 11, where said products are maintained in a commingled state by a circulating agitation. The circulating agitation in reaction chamber 11 is produced by taking suction through the pipes 12, 14 and 16 by pump 19 and discharging through the pipe 20 back into reaction chamber through the pipe 24, valve 21 being closed and valves 13, 15, 17 and 23 being open. As soon as the reaction is complete, the contents in the reaction chamber 11 are discharged to a separator 27, passing through pipes 22, exchanger 6 and cooler 45. In some cases, it may be desired to operate continuously, in which case a circulating agitation is maintained in the reaction chamber 24 and at the same time the oil containing the commingled agents is continuously discharged into the said separator tank 27. The oil containing the commingled agents pass through exchanger 6 in counterflow heat exchange to the incoming oil to be treated, thereby imparting a portion of the heat to the untreated oil, after which the oil containing the commingled water solution of caustic soda and suspended manganese dioxide is cooled to approximately 70° F., during the passage through the cooler 45. From the cooler 45 the treated oil and spent agents pass into the separator 27 where the spent water solution of caustic soda containing the spent manganese dioxide settles to the bottom and is drawn off into the tank 32 passing through a pipe 30 controlled by the valve 31, and the purified oil passes out the top of the separator, passing through the pipe 28 and into the treated oil tank 29.

The sweetening medium employed for this purification as heretofore stated, comprises

a mixture of manganese dioxide suspended in an aqueous solution of a caustic alkali; preferably a solution of caustic soda is used ranging from 15 Baumé to as high as 25 Baumé or higher, and commingling therewith from 1 to as high as 5 per cent or more by weight of manganese dioxide.

This sweetening medium may also be used at atmospheric temperature, if the medium is allowed to stand in contact with the sour gasoline for several days in a receptacle, at atmospheric temperature, the gasoline becomes "sweetened" and negative to the "doctor test". To carry out this step in the process, approximately 5 per cent of the sweetening medium is brought in contact with the "sour" gasoline preferably a mild agitation either continuous or intermittent, is maintained and within 5 days the gasoline will have become "sweet". This treatment is preferably carried out in storage tanks.

The mixing of these agents is diagrammatically shown in the drawing, 46 being a mixer tank of any preferred type containing the steam heating coils 50. The caustic soda is introduced into the mixer through the pipe 37 and the manganese dioxide in the required proportions is introduced into the mixer tank 46 through the man hole 51. The water solution of caustic soda containing the required percentage of manganese dioxide is commingled by an air agitation through the air inlet pipe 38. The mixing of the water solution of caustic soda and manganese dioxide may be carried out continuously or intermittently as the case demands and is preferably heated to a temperature of approximately 200 to 220° F.

The spent solution of caustic soda and manganese dioxide contained in the tank 32 may be partly recovered for re-use by methods well known in the art.

It is to be understood that any petroleum stock may be treated by this method for the removal of any sulphur bodies having the general formula RSH in which R may be hydrogen or any organic radical.

As a specific example, in the treatment of gasoline stocks derived from cracking California petroleum oil distillates, it was found that the amount of caustic soda solution of 25 Baumé containing 1 to 5 per cent by weight manganese dioxide ranging from 5 to as high as 15 per cent by volume, would remove satisfactorily the mercaptans, hydrogen sulfide and free sulphur from the same. It was found desirable in all cases to use a considerable excess of the purifying agents and thereafter recovering the agents by methods well known in the art.

By the term "sour" we means a petroleum oil containing mercaptans, hydrogen sulfide, or any other sulphur compound that reacts with the doctor solution, and by the term "sweet" we means a petroleum oil substan-

tially free of the above named sulphur constituents. By the term "doctor test" we mean that well-known test employed by chemists to determine a "sour" or "sweet" petroleum oil stock, the term "negative to doctor test" meaning that oil stock is "sweet"; positive to the doctor test" meaning that the oil stock is "sour." It is also to be understood that any gasoline stock or petroleum oil distillate may be treated by our invention and rendered "sweet", and that any petroleum oil distillate may or may not have had prior treatments known in the art, such as treatments with acid and caustic soda before being "sweetened" by our invention.

Preferably, this treatment is followed by a distillation with steam at a temperature approximately not exceeding 325° F. in order to obtain a finished water white gasoline stock which will retain a water white color and remain sweet to the "doctor test." However, it is to be understood that this treatment may or may not be followed by a distillation operation, this depending upon the stock to be treated and the color desired. In case a colored gasoline is to be manufactured, a distillation operation may not be necessary.

By the term "caustic alkali" we mean either caustic soda or caustic potash. While the process herein described is well adapted for carrying out the object of the present invention, it is understood that various modifications may be made without departing from the spirit of the invention and the invention includes all such modifications and changes as come within the scope of the appended claims.

We claim:

1. A process of purifying liquid hydrocarbons comprising treating the same with an aqueous solution of caustic alkali containing suspended manganese dioxide at an elevated temperature and under sufficient pressure to substantially prevent vaporization of the hydrocarbons and the aqueous solution of caustic alkali to render the hydrocarbons "sweet" to the "doctor test", then separating the treated hydrocarbons from the residual aqueous solution of caustic alkali and manganese dioxide compounds and distilling the treated hydrocarbons at a temperature not greater than the temperature employed in the sweetening step.

2. A process of purifying liquid hydrocarbons comprising treating the same with an aqueous solution of caustic alkali containing suspended manganese dioxide at a temperature of approximately 325° F. to substantially immediately oxidize the sulphur bearing constituents and to render the hydrocarbons "sweet" to the "doctor test", and separating the treated hydrocarbons from the residual aqueous solution of caustic alkali and manganese dioxide compounds, and distilling the treated hydrocarbons with steam at a temper-

ature substantially not greater than 325° F. In testimony whereof we affix our signatures.

JOHN C. BLACK.
